UNITED STATES PATENT OFFICE.

CALEB E. SUMMERS, OF DAYTON, OHIO, ASSIGNEE TO GENERAL MOTORS RESEARCH CORPORATION, OF DAYTON, OHIO, A CORPORATION OF DELAWARE.

INDICATOR.

Application filed April 17, 1922. Serial No. 554,344.

This invention relates to an indicating device especially adaptable to air-cooled internal-combustion engines. With such engines it is very necessary that the cooling fan or 5 blower is operating properly at all times for if by any chance it should fail to operate for any cause, such as the breaking of the fan belt or other driving means, the engine will quickly become overheated with consequent disastrous results to the cylinders, pistons, 10 valves, etc. For this reason it is most important that the operator be informed immediately when anything goes wrong with the air cooling means and before the engine has 15 reached high temperatures.

It is also of great importance that the operator be informed immediately when anything goes wrong with the lubricating system of the engine. In either of the above cases the 20 operator should immediately stop the engine and determine the cause of the trouble before proceeding further.

Among the objects of this invention is to provide a simple and substantial pneumatic 25 indicator which is durable, easily observed, and effective at all times.

Another object is to provide a single indicator which will indicate whether or not both the cooling system and lubricating system are 30 functioning properly, whereby the operator is required to watch only one indicator instead of two. Thus the probability of his noticing either of these serious troubles immediately is greatly increased.

Another object is to position the carburetor adjusting levers on the same plate and in close proximity of the cooling and lubricating indicator so that the operator may observe the position of them all at a mere glance. This compact arrangement also greatly cheapens the 40 cost of manufacture and installation upon a machine, such as upon the dash of an automobile.

Further objects and advantages of the present invention will be apparent from the following description, reference being had to the accompanying drawing, wherein a preferred form of embodiment of the present invention is clearly shown.

50 In the drawing:

Fig. 1 is a more or less diagrammatic view of an air cooled automobile engine showing the float operated electric switch in the engine lubricating system and the pneumatic indica-

Fig. 2 is a plan view of the combined indicator and carburetor adjusting levers mounted thereon.

Fig. 3 is a side elevation of the indicator.

Fig. 4 is the dash or operator's view of the 60 indicator.

Fig. 5 is a section through the float operated electric switch in the lubricating system.

Similar reference characters refer to similar parts throughout the several views. 65

Numeral 10 designates the internal combustion engine in its entirety having the cylinders 11, the crank case 12, and the fan housing or draft tube 14, and the centrifugal fan 15, which draws air upwardly around the engine cylinders 11 and out through the periphery of the fan 15. The indicator which is designated in its entirety by numeral 20 is suitably attached to the instrument dash 21 of the automobile and in plain view of the 75 operator. A pneumatic tube or duct 22 leads from the indicator 20 to the draft tube 14 of the engine and has an air tight attachment thereto by means of nipple 23.

The indicator 20 includes a main body casting 25 to which the duct 22 is suitably fastened by means of the nipple 26. The duct 22 is continued through the casting 25 by the horizontal passage 27 and the vertical passage 28 which in turn leads into the short 85 transparent cylinder 30, preferably of glass, which is cemented into the boss 29 of the casting 25, thus making an air tight joint therewith. A light ball 31, preferably of pith, rides loosely in the glass cylinder 30 and is 90 capable of being drawn up against the seat 28 by the depression in the draft tube 14 when the cooling system is functioning properly but heavy enough to drop down to the lower part of the tube 30 when the depression 95 in draft tube 14 decreases to a dangerous point. The face plate 32 which is rigidly fastened to casting 25 by means of screws or bolts 33 has an opening 35 cut therein so that the indicator ball 31 is visible to the operator only when it is in the lower part of the tube 30, and invisible when it is being held up against the seat 28 at the top of the tube 30. Thus it is seen that whenever the operator notices the indicator ball (which is preferably colored in contrast with the face plate) 100 in view he knows something is wrong.

In addition to the indicator being used to give warning of trouble in the cooling system it is also used to give warning of trouble 110

in the lubricating system of the engine as follows. An electric switch 40 is arranged to be closed by a float 41 whenever the lubricating oil is not flowing properly. In the particular 5 form shown, as long as the lubricating system is functioning properly, oil constantly flows through pipe 42 into the cup 43 which fills until it runs over the top, thus holding the float 41 up and holding the electric contact points 44, 45 apart. However, when the flow through the pipe 42 stops or drops off due to the trouble in the lubricating system the oil level in cup 43 will drop due to oil flowing out of the hole 46 faster than it is 10 running in, and hence the float 41 will drop and close the contact points 44, 45 of the switch 40. The ungrounded terminal 47 of the switch 40 has a wire 48 connected therewith which leads to the electro-magnet 50 15 supported upon the casting 25. The other terminal 49 of the electro-magnet is grounded through the ignition switch of the engine to complete the circuit when switch 40 and the ignition switch are both closed. The armature 51 of the magnet 50 has a pivotal connection to the casting 25 at the point 52 and a tension spring 53 is attached thereto which holds the armature 51 in the dotted position 51' when the magnet 50 is not energized. 20 When the armature is drawn to the full line position (see Fig. 3) its projecting end 55 closes the open end of the indicator tube 30 by fitting snugly thereagainst. Thus it is obvious that when the electric switch 40 is 25 closed by any failure whatever in the lubricating system of the engine the electro-magnet 50 will be energized and cause the valve end 55 of the armature 51 to close off the passage of air into tube 30 and cause the ball 31 to drop due to gravity from the top of the tube where it was held by the suction in 30 draft tube 14 to its lower visible position (see Fig. 4).

Therefore, whenever the operator sees the ball 31 he knows it is due to one of two causes, namely, either the cooling system or the lubricating system is not functioning properly, and that he should immediately 35 stop and investigate.

Of course when the engine is not running the ignition switch is turned off and hence no electric circuit is made by the closing of the electric switch 40. 40

In this invention it is preferred to also 45 mount the carburetor adjusting levers on the indicator instrument though either one or both of these may be mounted elsewhere if desired. However, it is a great convenience to be able to see at one glance that the carburetor adjustments are properly set and that 50

the air and oiling systems are working properly. The two bent levers 60 and 70 are pivotally mounted on the casting 25 by means of the screws 61 and 71. The lower arms of the levers are connected to Bowden wires 62 and 72 respectively which are enveloped by the guide tubes 63 and 73 having their upper ends fixed in the lugs 64 and 74 on the casting 25. The handles 65 and 75 of the levers 60 and 70 extend through slots 66 and 76 in the face plate 32. Each of these slots may be provided with a scale, as shown in Fig. 4, to show more exactly the position of the handles 65 and 75. The levers and Bowden wires may be used for operating any engine or other 55 adjustments, however, they are ordinarily used for making carburetor adjustments, such as the operation of the choke valve in starting, and a carburetor richness adjusting means. 60

While the form of mechanism herein shown and described, constitutes a preferred form of embodiment of the present invention, it is to be understood that other forms might be adopted, all coming within the scope of the 65 claims which follow.

What I claim is as follows:

1. In combination with an internal combustion engine having a draft tube, a pneumatically operated indicator, a duct leading 90 from the indicator to the draft tube, means within the duct to indicate the tendency of air to flow therethrough, means to close the duct, and means operable by a second abnormal condition in the engine for controlling 95 said closing means whereby said second condition is also indicated by the indicating means.
2. In combination with an internal combustion engine having an air cooling system, the 100 cooling system including a draft tube, a suction operated indicator adapted to be positioned at a distance from the engine, a conduit leading from the external atmosphere past the indicator and to the draft tube where- 105 by the pressure conditions in the draft tube actuate the indicator, a valve for controlling the flow of air through said conduit, a magnet operatively connected with said valve to operate the same, a float the position of which 110 is dependent upon the level of oil in the oiling system of the engine, and an electric circuit having associated therewith a circuit opening and closing device which is controlled by said float and which circuit includes the 115 magnet aforesaid.

In testimony whereof I hereto affix my signature.

CALEB E. SUMMERS.
